[57] **CLAIM**

The ornamental design for a tape cartridge for tape printer, as shown and described.

DESCRIPTION

FIG. 1 is a top plan view of a tape cartridge for tape printer;
 FIG. 2 is a bottom plan view thereof;

FIG. 3 is a front view thereof;
FIG. 4 is a rear view thereof;
FIG. 5 is a left side view thereof;
FIG. 6 is a right side view thereof; and,
FIG. 7 is a perspective view thereof.

The solid black areas in FIGS. 1-4, 6 and 7 are due to shadows produced during photography. It should also be understood that there is no ornamentation on the interior surfaces.
